UNITED STATES PATENT OFFICE.

MEADE LAFAYETTE ZIMMER, OF CORDOBA, ARGENTINA.

ROTARY INTERNAL-COMBUSTION ENGINE.

Application filed August 2, 1922. Serial No. 579,246.

This invention relates to an internal combustion engine of the rotary type. The principal objects of the invention are to provide a construction of very simple character which will be very light per unit horse power and can be made at small cost by any mechanic without any especially designed machines or tools; to provide such a machine of such simple construction, lightness, efficiency and cheapness as to render it especially valuable for manufacture and in small quantities and yet of such a nature that when manufactured in large quantities it can be put out on a very small cost basis. More specifically, the invention involves a construction comprising a cylindrical casing serving as a fly wheel adapted to rotate about a stationary shaft which carries elements for cooperating with the features of the casing to provide a pair of explosion chambers adapted to receive a compressed charge, explode it, and exhaust it; and also to provide within the casing a compression element and to rotate the latter at the same speed as the casing but in the opposite direction so that it can be made substantially like the explosion chambers but will operate twice as fast so as to provide for compressing the charges for them alternately and thus reduce the size of the engine relative to the horse power generated.

An important feature of the invention consists of an expansion ring adapted to be forced around on the spiral which constitutes the internal element of the explosion and compression chambers. This takes up the contraction between the casing and the eccentric and is adapted to prevent the passage of gas so as to constitute a substitute for the ordinary piston rings. With this I provide a substantially perfectly gas tight cylinder and it permits of such a loose adjustment of the expansion ring that the motor will turn with ease.

Additional objects and advantages of the invention will appear hereinafter.

Reference is to be had to the accompanying drawings, in which

Fig. 1 is a side view, partly in central section, of a preferred embodiment of this invention;

Fig. 2 is an end view;

Fig. 3 is an end view with the end piece removed showing the shaft in section on the line 3-3 of Fig. 1;

Fig. 4 is a similar view on the line 4-4 of Fig. 1;

Fig. 5 is an enlarged edge view of the expansion ring and the parts for closing its ends;

Fig. 6 is a side view of the same;

Fig. 7 is a sectional view on the line 7-7 of Fig. 1, showing the gearing for rotating the compression element;

Fig. 8 is a sectional view of the same on the line 8-8 of Fig. 7;

Fig. 9 is a sectional view on the line 9-9 of Fig. 2, showing the construction for introducing the fuel and air;

Fig. 10 is a sectional view on the line 10-10 of Fig. 9, showing the port through which the fuel and air pass into the cylinder;

Fig. 11 is an edge view of the device through which the gas enters the end of the cylinder;

Fig. 12 is an end view of the same;

Fig. 13 is a side view of a sliding valve between two of the chambers;

Figs. 14, 15, 16 and 17 are diagrammatic transverse sectional views on the line 14-17 of Fig. 22, of one of the explosion chambers, showing the parts in four different positions;

Figs. 18, 19, 20 and 21 are similar views of the compression chamber on the line 18-21 of Fig. 22, showing the positions of the parts at the instants represented by Figs. 14, 15, 16 and 17 respectively, and showing in dotted lines the positions of the piston of the other explosion chamber, and

Fig. 22 is a diagrammatic longitudinal central sectional view of the casing and ends with the interior parts removed.

I have shown the invention in a form in which a base 10 is employed having end standards 11 for supporting the whole device. Through these standards extend two non-circular passages in alignment in which is carried a shaft 12 which extends the whole length of the device and has its ends broached off to fit the passage and hold it firmly in stationary position. This shaft is provided with a ball bearing 13 at each end having the usual cones and adjusting devices. On these bearings are supported two end pieces 14 and 15. These end pieces are secured to two cylinders 16 which are just alike in all respects and which provide the two explosion chambers. Between them is fixed a third cylinder 17 which contains the compression chamber. These three cylinders 16, 16 and

17 are fixed rigidly together and also rigidly fixed to the ends 14 and 15 and they constitute the rotary element of the machine. They can be shaped in the form of crowned 5 pulleys and the power taken from them by belts or they can be provided with a gear securely fixed to the small cylindrical part at one or both ends or, in fact, the power can be transmitted from them in any of the ordinary ways.

It will be noted that the shaft 12 is shown at one end as provided with passages intended to be connected with oil reservoirs, and the end pieces 14 are provided with chambers 15 20 communicating with them through their radial ends and with a passage 18 through which the oil is pumped into the oil chamber and ball bearing for lubricating purposes.

20 The end of the shaft in addition to the oil passage 18 is provided with an air passage 19 to admit air to the oil chamber and also with a tube 8 through which the oil is siphoned out of the oil chamber when the

25 motor is at rest. The air is vented from the oil chamber through the passage 19 to permit the oil to be pumped in. As soon as the motor stops the chamber 20 is emptied by oil siphoning out promptly through the tube

30 8. This tube is not absolutely necessary for the functioning of the engine but is highly desirable for various reasons. If the oil were allowed to remain in the chamber with the motor at rest there would be a tendency

35 for the oil to leak into the combustion chamber and be forced out and wasted at the first turn of the motor on starting. The starting of the motor would be made a good deal harder especially in cold weather. The

40 circulation of the oil while the motor is running also serves to cool the interior of the motor on account of the cool oil being continually pumped into the chamber and the heated oil forced out through the tube 8.

45 Moreover, as the oil is not allowed to stand in the chamber no oil sediment collects in it but it collects in the oil reservoir outside from which it is easily removed.

One of the ends 14, 15 also is provided 50 with an annular groove 22 which is designed to be connected with a source of explosive fuel provided through a carburetor 29. This constitutes the intake for the explosive mixture. Air is admitted with it around this

55 groove 22. This intake is provided with a ring 23 in the groove 22 carrying suction vanes and running past the nozzle of the carburetor to spray the gasoline into the intake passage 24. This is a passage in the

60 casting which constitutes the end piece and it is connected with a passage 25 extending through the wall of the cylinder 16. In the wall of the central cylinder 17 is a fuel passage 26 registering with the passage 25.

65 This passage 26 has a port 27 for conducting

the mixed fuel and air into the compression chamber 17.

The compression chamber 17 is of cylindrical form outside with flanges by which it is secured to the two explosion cylinders. 70 Its flat end walls 30 have arcuate recesses 31 and the ports 26 and also recesses 32 for the valves, as will appear. Otherwise these ends are flat and continuous. The cylinders 16 are substantially like them and the two 75 pairs of registering recesses 31 are filled with lead to form a counterpoise. The inner edges of all these ends in both kinds of cylinders are circular and concentric with the shaft. Inside these edges fit the ends of expansion rings 33 in all these cylinders. The inner surface of each expansion ring is slit 80 radially at short intervals to facilitate its flexing and the inner surface is curved in the form of a plane spiral while its outer 85 surface is cylindrical.

As stated above, the shaft 12 is stationary. Fixed on this shaft in each of the two explosion cylinders 16 is a hub. Each of these central hubs is keyed to the stationary shaft 90 12 and has integral arms projecting therefrom and a rim 40 around them forming a spider 40 having a spiral outer surface on which fits the expansion ring 33 having a similar shape inside. As the rim of this 95 spider is of special significance I refer to it sometimes as the rim 40. This central hub has two pairs of passages therethrough parallel with each other for two pairs of springs 41. These springs are mounted on rods 42 100 and at the end these rods pass into a yoke 43 which is guided by the side of the passages in the hub. The springs bear on the inner surface of the rim and the yoke 43 and tend to force the yoke outwardly in a radial direction at all times. On the yoke 43 is mounted a blade or piston 44. I have shown it as having a recessed end at 45 but the edges of this end constitute bearing surfaces. These surfaces bear against the interior surface of the cylinder 16, which is 110 of cam formation and in the general shape of a heart cam 46. The rotation of the cylinder about the stationary shaft causes this piston to move in and out radially on account of the shape of the cam surface 46. The springs 41 keep the end of the piston in contact with the cam surfaces at all times. The piston 44 is also provided with expansion plates 44 for maintaining a gas-tight joint between the sides of the piston and the walls of the cylinder. 120

Mounted on the spiral outer surface of this rim 40 is the spiral expansion ring 33 above described. This is not a complete 125 ring but it is provided with a longitudinal projection 52 at each of its ends adapted to almost abut together and having a narrow longitudinal space for a series of closing plates 53, 54 and 55, there being two of 130

the latter, one at each end. These plates are arranged to fit each other so as to keep the spiral expansion ring tight around the radially reciprocating piston or blade at all times. The plates 53 and 54 are provided with projections 56 at their opposite ends sliding in notches in the projections 52 in the ends of the expansion ring and they are provided with overlapping ends 57 which move on each other. The plates 55 are for the purpose of closing the joint between these plates 57. A V-shaped spring 58 is located at each end of the cylinder fitting in openings 59, one in each of the plates 53 and 54 to normally hold them in proper position tight against the projections 52. These springs project inwardly and are supported inside the hub and they are set so that the legs tend to draw the plates 53 and 54 toward each other.

This expansion ring, as stated, is mounted on the rim which is located on the rim 40 in the cylinder. It is provided with a spring 60 tending to push the spiral expansion ring around the spiral hub to keep it tight. It accomplishes this by acting on a lever 61 pivoted at 62 on the hub and entering through an opening 63 in a notch in the expansion ring to operate it. The explosion and compressing cylinders are formed substantially alike except that the rims 40 in the explosion cylinders are keyed to the fixed shaft 12 while the rim 40 in the central compression cylinder rotates thereon.

The compression cylinder is connected with the two explosion cylinders through two ports 34 opposite to each other as shown in Fig. 22. Each of these ports is closed by a valve 35 located in the recess 32, pivoted on a stud at 36, and having a pin 37 which pivotally connects it with an operating slide 38. These operating slides are moved back and forth to open and close the ports 34 as shown in Fig. 13 by a pair of cams 39. These valves control the passage of the compressed explosive mixture from the compression chamber into the explosion chambers alternately and each one is opened once during each rotation of the cylinder. The two explosion cylinders are located with their cams 46 in opposite positions circumferentially, the right hand one in Fig. 1 registering with the cam in the compression cylinder.

On the inner circumference of one, or preferably both, of the explosion cylinders there is an internal gear 67 meshing with a smaller gear 68 inside rotatable on a stationary shaft 69 fixed on the end of the explosion cylinder and having on it a pinion 70 meshing with a gear 71 fixed to the end wall of the compression cylinder. This is duplicated on the other end. The gear ratios of the two pairs of gears are the same so that the internal gear wheel 67, rotating

constantly in the forward direction, will turn the gear 68 with it and also the gear 70, which will turn the gear 71 in the opposite direction at the same speed. This permits of the use of two explosion chambers for one compression chamber as stated above. The compression chamber compresses a charge and gets it ready to deliver to an explosion and expansion chamber twice during each rotation so that each explosion chamber provides an explosion once during each rotation and these explosions occur 180° apart. Thus, the effect of the machine is a double explosion per revolution of the casing.

The operation will be understood more fully by reference to the last sheet of drawings. Fig. 22 shows the course of the explosive mixture into the compression chamber. In the position shown in Fig. 18 the mixture has been drawn into the compression chamber by its rotation and it is filled. Now, as the casing continues to rotate in one direction and the piston in the other, the parts come to the position shown in Fig. 19 in which the mixture previously drawn in is being compressed at the top of the figure while a fresh mixture is being drawn in at the bottom. Now the valve 35 on one side opens and the compressed charge is let into one of the explosion chambers. Fig. 20 shows the next position, 180° from Fig. 18, in which the first mixture has all been compressed and forced out into one of the explosion chambers as shown in Fig. 14 through the port 34 and a new charge has been fully introduced into the compression chamber ready for compression. Fig. 21 shows the last position which, in effect, is the same as in Fig. 19 although the parts are in the opposite position and the other valve 35 opens and lets the second compressed charge into the other explosion chamber through the port 34 on that side. Figs. 18 and 20 have the same relation to each other also. At this instant the other explosion chamber is in the position shown in Fig. 17, but the piston 44 thereof is in the opposite position 180° away where it is permanently located.

While these operations are going on in the compression chamber, the pistons in the explosion chambers, of course, are not rotating, as stated, but the chambers themselves are rotating with the casing of the compression chamber. Figs. 14 and 18 show one position of the parts. The mixture, as stated, has been drawn into the compression chamber but is not yet being discharged into the opposite explosion chamber. As the parts move from the position shown in Fig. 18 to that shown in Fig. 19, the explosion cylinder moves from the position shown in Fig. 14 to that shown in Fig. 15 one quarter of a revolution and the compressed mixture shown in Fig. 19 is ready to be forced

into the opposite cylinder through the port 34, the valve 35 opening automatically as stated. The explosion of the compressed mixture shown in Fig. 14 takes place at the 5 groove 73 provided to ensure a little space for the explosive mixture where the spark is caused in the usual way. Fig. 15 shows the expansion and the fact that the cylinder is forced around from the stationary piston by 10 the expansion. The same cylinder then comes to the position shown in Fig. 16 in which one half a revolution has been accomplished and the power of the explosion is about exhausted. The compression chamber 15 is now in the position shown in Fig. 20, having fully charged the opposite cylinder which is then in the same position relative to the piston as shown in Fig. 14 and ready to be exploded. It will be noted that the 20 piston of the opposite cylinder being 180° from that shown in Fig. 14 points in the opposite direction from the shaft. In Fig. 17 the exhaust takes place through ports 74 and the parts are then ready to receive a 25 new charge in the position shown in Fig. 14. It will be noted that the two pistons 44 in the two explosion chambers are located always exactly in the same position because 30 stationary. They are shown also as extending in the opposite direction from the shaft, being 180° apart. The two explosion chambers are fixed together so as to be in opposite 35 positions relative to the pistons.

The ignition system can be the same as for 35 other motors and is not shown except for binding posts 72. No timer has been shown in the drawings, but this also would be attached to the end piece opposite to that which contains the intake and would be of 40 one of the ordinary kinds.

From this description, it will be seen that 45 considerable space is saved by rotating the compression chamber effectively at twice the speed of the explosion chambers so as to use one compression chamber to supply two explosion chambers. Also an increase in power is secured by this means for two explosions are provided for at each revolution. All 50 ordinary inlet and nozzle valves are entirely avoided, the only valves being used are those between the compression and the explosion chambers which work very simply and which will not give very much trouble on account of wear. Most of the bearing surfaces are 55 at the points where the side pieces revolve on the expansion ring but these surfaces are so narrow that they do not create much friction and they can be lubricated by means of an oil groove.

60 The cylinder can be maintained gas tight with comparatively loose adjustment of the expansion ring so that the motor will run with the greatest freedom. This expansion ring is an important feature of the invention as it automatically provides for contraction

and expansion and prevents escape of the fuel at all times. The force exerted by the expansion of the exploded charge against the stationary piston or blade located in a radial position is applied at right angles to the 70 radius nearly throughout the whole 360 degrees of the circumference. The motor is very simple in construction and extremely light per horse power. Almost any mechanic can make it without specially designed machines or tools and at small cost. No carburetor in the ordinary sense has to be employed as the intake ring takes up the fuel and sprays it into the intake.

Although I have illustrated and described 80 only a single form of this invention, I am aware of the fact that modifications can be made therein by any person skilled in the art without departing from the scope of the invention as expressed in the claims. Therefore, I do not wish to be limited to all the details of construction herein shown and described, but what I do claim is:—

1. In a rotary internal combustion engine, 90 the combination of two explosion cylinders and one compression cylinder rotatable in the same direction, and means for compressing the explosive mixture twice in the compression cylinder to every explosion in each of the explosion cylinders, whereby charges of 95 the explosive mixture can be introduced from the compression cylinder into the two explosion cylinders, alternately, during a single revolution, and two explosions can be obtained.

2. In a rotary internal combustion engine, 100 the combination of two explosion cylinders and one compression cylinder fixedly connected together and rotatable about an axis, a piston in each cylinder, and means for 105 rotating the piston in the compression cylinder in the opposite direction to the rotation of the cylinder itself.

3. In a rotary internal combustion engine, 110 the combination of two explosion cylinders and one compression chamber, fixedly connected together and rotatable about a common central axis, a piston in each cylinder, means for rotating the piston in the compression cylinder in the opposite direction 115 to the rotation of the cylinder itself and at the same speed, and means for holding the pistons in the explosion cylinders stationary during the entire rotation.

4. In a rotary internal combustion engine, 120 the combination of a shaft, one compression and two explosion cylinders fixed together and rotatable together about said shaft, means for conducting an explosive mixture into the compression cylinder, a piston in 125 the compression cylinder, means for rotating said piston in the opposite direction to the rotation of the cylinder and at the same speed, a piston in each explosion cylinder, all of said cylinders having an internal cam 130

formation for cooperating with the respective pistons, whereby the charge introduced into the compression cylinder will be compressed in one half of a revolution, and means for conducting the compressed charges alternately into the two explosion cylinders to provide two explosions per revolution.

5. In a rotary internal combustion engine, the combination of a stationary shaft, one compression cylinder and two explosion cylinders fixed together and rotatable about said shaft, means for conducting an explosion mixture into the compression cylinder, a piston in the compression cylinder located radially, means for rotating the piston in a direction opposite to that in which the cylinder rotates, and at the same speed, stationary pistons in the explosion cylinders, all of said cylinders having an internal cam formation for cooperating with their respective pistons, and means for conducting the compressed charges alternately into the two explosion cylinders.

25 6. In a rotary internal combustion engine, the combination of a stationary shaft, one compression cylinder and two explosion cylinders fixed together and rotatable about said shaft, means for conducting explosive mixtures into the compression cylinder, means in said compression cylinder for compressing the mixture during one half of a revolution, ports for conducting the explosive mixture from the compression cylinder into each of the explosion cylinders, valves for closing said ports, means to automatically operate said valves, means in each explosion cylinder for receiving the impact of the explosion and transmitting it to the cylinders to rotate them, said means in the two explosion cylinders being located oppositely with respect to each other, whereby each one will provide an explosion during one revolution of the cylinder, said explosions being 180° apart.

7. In a rotary internal combustion engine, the combination of rotary casing, two explosion cylinders and one compression cylinder in said casing rotatable in the same direction, means for introducing an explosive mixture into the compression cylinder, means in said cylinder for compressing two charges during each revolution of the casing, means for introducing one of said charges into one of the explosion cylinders and the other into the other, and means in said explosion cylinders for igniting the two charges therein once during each revolution.

8. In a rotary internal combustion engine, the combination of a rotary casing, two explosion cylinders and one compression cylinder in said casing rotatable together, means for introducing an explosive mixture into the compression cylinder, means in said casing for compressing two charges during each

revolution of the casing, means for introducing one of said compressed charges into one of the explosion cylinders, and other into the other, means in said explosive cylinders for igniting the charges alternately once 70 during each revolution, two valves for controlling the conduction of the compressed charges from the compression cylinder into the explosion cylinders, and two cams, one mounted on each side of the compression cylinder and 180° apart, one for operating each of said valves.

9. In a rotary internal combustion engine, the combination of a rotary casing, said casing being divided up into three compartments, the central one constituting a compression chamber and the two end ones explosion chambers, the interior of said casing in each of the chambers being in the form of a heart-shaped cam, a piston in 80 each of the three chambers, the pistons being yieldingly mounted to move radially against the surfaces of said cams, whereby the pistons will contact with said surfaces throughout each revolution, means for holding the pistons in the explosion chambers against rotation, means for rotating the piston in the compression chamber in the opposite direction to that of the casing and at the same speed, the inward extension in the 85 cam surface of the compression cylinder being located substantially in the same position as that of one of the explosion chambers and in the opposite position to that of the other.

10. As an article of manufacture, an expansion ring for a rotary engine having an outer circular surface and an inner spiral surface extending from a thin end of the ring substantially throughout a circle to an 105 opposite thick end of the ring and an inner spiral body around which said ring is rotatable to expand the ring, the inner concave surface of the ring having radial slots.

11. In a rotary internal combustion engine, the combination of a stationary shaft, a rotary cylinder having a cam-shaped surface inside, a piston mounted radially within said cylinder, yielding means for forcing said piston outwardly in a radial direction 110 against said cam surface to form a tight joint, and means for rotating said piston at the same speed as the cylinder but in the opposite direction and about the same axis.

12. In a rotary internal combustion engine, the combination with a stationary shaft, a rotary casing having a cam-shaped surface inside, and a piston mounted radially within said casing, of a pair of rods on which the piston is guided to reciprocate, 125 a pair of springs on the rods for holding the end of the piston at the extreme radial position, a spider on the shaft on which said rods are located, said spider having a spiral formation about the shaft, the casing being 130

provided with a passage of concentric circular form in which said spider is located, and an expansion ring between the surfaces of the spider and casing for preventing the passage of the explosive mixture between them.

13. In a rotary internal combustion engine, the combination with a shaft, a rotary casing having a cam-shaped surface inside, 10 and a piston mounted radially within said casing, of yielding means for supporting said piston with its end against said cam surface, a spider on said shaft for supporting said piston, said spider having an outer surface 15 of spiral formation and the casing having an inner concentric circular surface within which the spider is located, and an expansion ring having an outer concentric circular surface fitting on the inside of the casing 20 and an inner spiral surface fitting on the outside of the spider, and capable of moving around the shaft to ensure a tight joint.

14. In a rotary internal combustion engine, the combination with a shaft and a 25 cylinder having a cam-shaped surface inside, said parts being relatively rotatable, of a piston mounted radially within said cylinder, means for yieldingly supporting said piston in a radial position against said 30 cam surface, a spider on said shaft for supporting said piston, said spider having an outer surface of spiral formation and the cylinder having an inner concentric circular surface within which the spider is located, 35 an expansion ring having an outer concentric circular surface fitting on the inside of the piston, and an inner spiral surface fitting on the outside of the spider, and capable of being moved circumferentially, 40 and means of a yielding nature for pressing the ring around the circumference when the space between the casing and spider commences to change.

15. In a rotary internal combustion engine, the combination of a shaft and casing, 45 relatively rotatable separately, a spider on said shaft, a piston mounted on said spider and adapted to move radially, the casing having a cam-shaped interior against which the end of said piston is adapted to engage to provide a chamber for the explosive mixture, the exterior of said spider and the interior surface of said casing at its ends having a space between them gradually 50 widening around the circumference, a tapered expansion ring fitting in and filling said space for preventing the passage of the explosive mixture between said parts, a lever mounted on the spider and engaging the expansion ring, and a spring on the spider for yieldingly forcing said lever in a direction to move the expansion ring around in a direction to ensure its filling the space 55 between the spider and casing.

16. In a rotary internal combustion engine,

the combination of a relatively rotatable shaft and casing, a spider on said shaft, a piston mounted on said spider and adapted to move radially, the casing having a cam-shaped interior against which the end of said 70 piston presses to provide a chamber for the explosive mixture, the exterior of said spider and the interior surface of said casing at its ends having a space between them, an expansion ring fitting in and filling said 75 space for preventing the passage of the explosive mixture between said parts, a lever mounted on the spider and engaging the expansion ring, a spring on the spider for yieldingly forcing said lever in a direction 80 to move the expansion ring around for filling the space between the spider and casing, said expansion ring being circular and concentric with the shaft on one side and of spiral formation on the other, the casing and spider being similarly shaped so that the expansion ring will fill the space in all positions.

17. In a rotary internal combustion engine, the combination of a relatively rotatable shaft and casing, a spider on said shaft, 90 a piston mounted on said spider and adapted to move on said spider and adapted to move radially, the casing having a cam-shaped interior against which the end of said piston presses to provide a chamber 95 for the explosive mixture, the exterior of said spider and the interior surface of said casing at its ends having a space between them gradually widening from one point to another, an expansion ring fitting in and filling said space for preventing the passage 100 of the explosive mixture between said parts, means for moving the expansion ring around in a direction to increase its capacity for filling the space between the spider and casing, said expansion ring being thicker at one end than at the other, and having a longitudinal space between its ends extending through its length, and means for closing 105 said space.

18. In a rotary internal combustion engine, the combination of a relatively rotatable shaft and casing, a piston adapted to move radially, the casing having a cam-shaped interior against which the end of said piston presses to provide a chamber for the explosive mixture, an expansion ring fitting inside the casing for preventing the passage of the explosive mixture, said expansion ring being thicker at one end than at the other, and having a longitudinal space between its ends extending throughout its length, means for closing said space comprising a pair of plates located along the edges of the expansion ring and interlocking with each other, and leaving a space between them for the piston, said plates being slideable circumferentially on each other, and two small end plates at the ends of the piston.

19. In a rotary internal combustion engine, the combination of a relatively rotatable shaft and casing, a spider on said shaft, a piston mounted on said spider and adapted to move on said spider and adapted to move radially, the casing having a cam-shaped interior against which the end of said piston presses to provide a chamber for the explosive mixture, the exterior of said spider and the interior surface of said casing at its ends having a space between them gradually widening from one point to another, an expansion ring fitting in and filling said space for preventing the passage of the explosive mixture between said parts, means for moving the expansion ring around in a direction to increase its capacity for filling the space between the spider and casing, said expansion ring being thicker at one end than at the other, and having a longitudinal space between its ends extending through its length, means for closing said space, said means comprising a pair of plates located along the edges of the expansion ring longitudinally of the shaft, and springs at their ends for normally holding them apart.
20. In a rotary internal combustion engine, the combination of a stationary shaft, and one compression and two explosive cylinders fixed together and rotatable together about said shaft, of means for conducting an explosive mixture into the compression cylinder, a piston in each of the cylinders, all of said cylinders having an interior cam formation for cooperating with the respective pistons, and means for conducting the compressed charges alternately into the two explosion chambers, said shaft having at the end passages for oil and air.
21. In a rotary internal combustion engine, the combination of an expansion ring for preventing the passage of the explosive mixture, said expansion ring being thicker at one end than at the other, and having a longitudinal space between its ends extending throughout its length, a piston movable through said space, means for closing said space around the piston comprising a pair of plates located along the edges of the expansion ring and interlocking with each other, and leaving a space between them for the piston, said plates being slidable circumferentially on each other, and two small end plates at the ends of the piston.
22. In a rotary internal combustion engine, the combination with a shaft and a relatively rotatable cylinder, the shaft having a hub having a spiral surface, of an expansion ring extending part way around the cylinder for preventing the passage of the explosive mixture, means for moving the expansion ring around in the cylinder, said expansion ring being thicker at one extreme end than at the other to fit on said surface, and having a longitudinal space between its ends extending through its width, a pair of plates located along the edges of the expansion ring longitudinally of the shaft, and springs at their ends for normally closing the space between the ends of the expansion ring.
23. As an article of manufacture, an expansion ring for a rotary engine having an outer concentric circular surface, and a single internal spiral surface, and capable of being moved circumferentially, and means of a yielding nature for pressing the ring circumferentially around the inner spiral body.

In testimony whereof I have hereunto affixed my signature.

MEADE LAFAYETTE ZIMMER.
